UNITED STATES PATENT OFFICE.

WILLIAM FULLARD, OF PLAINFIELD, NEW JERSEY, ASSIGNOR TO
TYMPALYN COMPANY, A CORPORATION OF MAINE.

PRINTING-MACHINE.

No. 833,036.

Specification of Letters Patent.

Patented Oct. 9, 1906.

Application filed February 1, 1905. Serial No. 243,606.

To all whom it may concern:

Be it known that I, WILLIAM FULLARD, a citizen of the United States, residing at Plainfield, Union county, State of New Jersey, 5 have invented a new and useful Improvement in Printing-Machines, of which the following is a specification.

My invention relates to printing-machines; and it consists of novel means for feeding the 10 sheet to the impression-dies.

It further consists in novel means for arresting the feeding device during the time of printing.

It further consists of novel means for holding 15 the sheet during printing.

It further consists of novel features of construction, all as will be hereinafter fully set forth.

Figure 1 represents an end elevation of a 20 printing-press embodying my invention. Figs. 2 and 3 represent side elevations thereof, taken from different sides. Fig. 4 represents a top plan view of a portion of the device on an enlarged scale and in detached position.

Fig. 5 represents a side elevation of a portion 25 of the feeding device on an enlarged scale. Fig. 6 represents a top plan view of the paper-holding device on an enlarged scale. Fig. 7 represents a side elevation thereof. Figs. 8

30 and 9 represent an end elevation of a portion of the paper-holding device. Fig. 10 represents a side elevation, in detached position and on an enlarged scale, of the means for arresting the paper-feeding device. Fig. 11

35 represents a detail view, in detached position, of the means for accomplishing the arresting of the feeding device.

Similar numerals of reference indicate corresponding parts in the figures.

40 Referring to the drawings, 1 designates a printing-machine consisting of a frame 2, in which is mounted the driving-shaft 3, carrying the driving-pulley 4, to which power is imparted from any suitable source, said shaft

45 3 also carrying the fly-wheel 5 and having a pinion 6 thereon, which meshes with a main drive-gear 7, which is mounted upon the crank-shaft 8, the latter carrying the bed-crank or separating-cam 9, which is in suit-

50 able engagement with the bed connection-arm 10, the latter being pivotally connected in any suitable manner, as by means of the pin 11, with the type-bed 12, which latter is mounted in a suitable portion 13 of the frame

and which serves as a guide for said type-bed, 55 it being understood that as the bed-crank cam 9 is rotated it imparts a reciprocating motion to the bed connection-arm 10, which thus reciprocates the type-bed 12 in order to bring the same into proper relation with the 60 platen 14, suitably supported upon the frame 2 of the machine in order to make an impression. Also in suitable connection with the bed-crank or separating-cam 9 is the sheet-separator lever 15, which latter is 65 fulcrumed upon the shaft 16, suitably carried in the frame of the machine, said lever 15 being in the form of a yoke at its upper portion and extending beyond the shaft 16 and its ends 19 serving as a support for the 70 shaft 17, said shaft having an opening 18 therethrough and upon which is mounted a feed-gripper cylinder 20, said shaft 17 also carrying the gear 21 and said cylinder being suitably provided with air-passages 22 there- 75 through extending to the periphery thereof and communicating with the opening 18 in the shaft.

23 designates a cam which is mounted upon the upper end 19 of yoke 15 and with 80 which is adapted to be brought into contact at the proper time the nose of the lever 24, which is suitably connected with a rod 25, carried by the feed-gripper cylinder 20, said rod carrying the grippers 26, which are situated adjacent the opening of the passages 22, it being understood that as the lever 15 is actuated by the bed-crank or separating-cam 9 the feed-gripper cylinder 20 and its adjuncts are reciprocated toward and away from the 90 feed-table 27, which is suitably supported upon the frame of the machine, the extent of the motion being understood from Figs. 2, 3, and 5.

Meshing with the gear 21 is a gear 28, carried upon the shaft 16, which also carries the tape-feed cylinder 29, around which passes the sheet-tape 30, which also passes around the roller 31, suitably supported with respect to the machine. 95

32 designates a gear carried by the tape-feed cylinder, which gear is in engagement with the belt or chain 33, which passes around the gear 34, supported on the sheet-apron driving-gear 36, which is carried by 100 the shaft 35, the latter being suitably mounted in the frame of the machine, and said gear 36 is in mesh with the gear 37, carried on the

crank-shaft 8, so that when motion is imparted to the crank-shaft 8 it operates the gear 37 and the gears 34 and 36, driving the shaft 35 when connected therewith, as hereinafter explained, the gear 34 operating the chain 33 and imparting motion to the tape-feed cylinder 29, while the shaft 35 operates the sheet-carrying apron 42.

38 designates a chain which passes around suitable gears carried on the shaft 35, so that motion is imparted to said chain 38, which also passes around the gears mounted on shaft 39, said shafts 35 and 39 carrying suitable apron-cylinders 40 and 41, around which pass the sheet-carrying apron 42, the same passing over the platen 14 and is held in proper position with respect thereto by means of an idler 43, so that when the chain 38 operates the cylinders 40 and 41 the apron is operated. In order to stop the movement of said apron during the time of the impression, I have provided certain mechanism therefor, which consists of a sleeve 44, keyed or otherwise secured to the shaft 35. In the present instance I have shown the same secured by a pin 45, said sleeve having a sheet-apron locking-cam 46 thereon, which thus rotates with the shaft. The gear 36 is mounted on said sleeve 44 and is loose thereon, and in order to lock the same to said sleeve, and consequently the shaft 35, I employ a washer-disk 47 with a suitable spring 48 bearing thereagainst and also against the locking-nuts 49, which are mounted on the threaded end 50 of said sleeve, whereby it will be seen that the said gear 36 is locked to the shaft by means of friction, and when motion is imparted to the gear 36, as before stated, by the crank-gear 37 the shaft 35 is rotated, and consequently the belt or chain 38 and the carrying-apron 42, so that as the sheet is fed down it is brought forward by the sheet-tape 30 upon the sheet-carrying apron 42. As it is necessary to arrest the movement of the carrying-apron, I employ a locking-lever 51, one end of which travels on the cam 46 and the other end of which is provided with a roller 52, which is in contact with the sheet-carrying apron stop-cam 53, suitably mounted upon the crank-shaft 8 and moves therewith, the said cam 53 being so timed as to permit the end of the locking-lever 51 to contact with the shoulder 54 of the locking-cam 46, which being keyed to the shaft 35 arrests the movement thereof, overcoming the tension of the spring 48, so that while motion is still imparted to the gears 36 and 34 the shaft 35 is prevented from rotating, thus stopping the movement of the sheet-carrying apron 42, it being understood, of course, that the type-bed 12 is so timed as to make an impression at the time that the paper is held stationary. The sheet-carrying apron stop-cam 53 continuing its movement will bring the nose 55 thereof into

contact with the roller 52, as best seen in Fig. 2, and raises the same, thus releasing the shoulder 54, so that by means of the friction of the gear 36 motion is imparted to the shaft 35.

56 designates a suction-pump which is suitably actuated by the eccentric 57, carried on the crank-shaft, and is connected by a pipe 58 to the passage 18 in the shaft 17, the said action of the pump being such as to create suction at the air-passages 22 in order to draw down the lowermost of the sheets 59, as best seen in Fig. 5, at the proper time, said pipe 58 having a flexible connection 60 intermediate its length in order to permit of the rocking movement to the feed-gripper cylinder 20.

61 designates a hopper or receptacle for the sheets or paper, the walls of the hopper being inclined rearwardly from the feed-opening, so that the sheets therein are held horizontal; but each sheet is slightly in advance of the sheet above, thus removing the weight of the sheets from the feeding-point and allowing the removal of the lowermost sheet with more ease. When a sheet is being removed, it is necessary to support at the feeding side of the hopper the next sheet, so that I provide a sheet-abutment 62, which consists of a suitable device adapted to pass beneath the paper and at the same time against the front end of the pile of sheets and which is supported by the carrier 63, movable in a suitable guide 64, connected with the frame of the machine, said abutment-carrier 63 having suitable connection with an arm 65, pivotally connected with the sheet-abutment shaft 66, which also carries the actuating-arm 67, the latter communicating with a suitable actuating-cam 68, mounted or connected with the tape-feed cylinder 29, so that as the latter is rotated the cam operates the actuating-arm in order to impart reciprocating motion to the carrier 63 in order that at the proper time the sheet-abutment is placed beneath the lowermost sheet, as before stated. The upper part of the abutment has an angle-piece to conform to the angle of the pile of sheets.

In order to direct the sheets to their proper position, I provide the side guides 69, which are carried by the rods 70, mounted in the frame of the machine, and upon which rods the side guides may be clamped and adjusted, said side guides having a suitable groove or passage 71 for the reception of the paper or sheet, it being seen that the paper is fed down from the tapes 30 to the sheet-carrying apron 42 into the side guides, and in order to stop the same at the proper point above the platen I provide sheet-stops 72, which are mounted upon the rock-shaft 73, the same being spring-actuated, if desired, and carried in a suitable lug 74, said rock-shaft 73 having levers 75 thereon for operating the same,

which are adapted to be engaged at the proper time by the plate 76, carried by the shaft 77, suitably mounted in the frame of the machine, said shaft 77 also carrying the 5 operating-lever 78, which is in engagement with a cam 79 for operating the arm, said cam being carried and locked in suitable accord with the tape-feed cylinder 29, it being seen that the said plate 76 is caused to hold 10 or depress the lever 75, carried on the shaft 73, in order to raise the sheet-stop 72 and permit forward movement of the sheet or leaf at the proper time.

The operation is as follows: Power being 15 imparted to the drive-pulley 4 causes the drive-shaft to rotate and imparts motion to the pinion 6 and to the main drive-gear 7. This in turn actuates the bed-crank or separating-cam 9, the cam 57 for operating the 20 suction-pump, the gear 37, and the sheet-carrying apron stop-cam 53. As already stated, the bed-crank 9 operates the connecting-arm 10 to impart a reciprocating motion thereto in order to move the type-bed 12 to 25 and from the platen. In order to feed a sheet to the position above the platen, the separator-lever 15 is so timed as to place the feed-gripper cylinder adjacent the lowermost sheet, the suction-pump 56 being operated 30 in order to cause the suction and draw down the lowermost sheet at the same time the sheet-abutment carrier 63 is actuated forward to pass beneath and abut against the sheets while the feed-gripper cylinder is 35 moving away from the feed-table 27, as best understood from Fig. 5, the same being accomplished by suitable movements of the lever 15. At the same time the cam 23 actuates the gripper 26 and causes the same to 40 engage with the sheet, as seen in Fig. 5, the motion being imparted to the feed-gripper cylinder 20 through the gear 21 and gear 28, the paper is brought around said cylinder 20 and is released by the gripper and passes 45 along with the sheet-tapes 30, to which motion is also imparted, the said sheet passing between the side guides 69 and upon the apron 42 until it assumes the proper position upon the platen beneath the type-bed 12, it having 50 come in contact with the sheet-stop 72. The type-bed is now actuated to make an impression; but in order to arrest the movement of the apron at the same time the end of the locking-lever 51 comes in contact with the 55 shoulder 54 of the apron-carrier cam 46, as described, thus arresting the movement of the shaft 35 and preventing movement of the apron until the impression has been taken, after which the operation as above described is repeated, it of course being understood that the sheet-abutments are reciprocated back and forward at the proper time and that the suction-pump is caused to 60 create a suction to draw down the lowermost sheet, which will immediately be engaged

by the gripper, and that after the impression is taken the plate 76 is operated in order to raise the stop 72 at the same time that the movement of the sheet-carrying apron 42 is started in order that the sheet can be removed from the press and another one fed to its place to receive the same.

It will be evident that various changes may be made by those skilled in the art which may come within the scope of my invention, 75 and I do not, therefore, desire to be limited in every instance to the exact construction herein shown and described.

Having thus described my invention, what I claim as new, and desire to secure by Letters Patent, is—

1. In a device of the character described, printing means, suitably-actuated sheet-feeding devices, spring-actuated frictional means for actuating the feeding devices and 85 positive means for arresting said feeding devices and the sheet during the impression.

2. In a device of the character described, a type or die bed suitably actuated, sheet-feeding devices, carrying means for said sheets, 90 spring-actuated frictional means for actuating the carrying devices, and positive means for arresting said carrying means and the sheets during the impression.

3. In a device of the character described, a 95 type or die bed, suitably-actuated sheet-feeding devices, spring-actuated frictional means for controlling the sheet, and means for automatically operating said frictional means whereby the sheet is arrested during the impression.

4. In a device of the character described, a type or die bed suitably actuated, a sheet-carrying apron, a gear suitably actuated, a shaft upon which said gear is mounted and 105 spring-actuated frictional means for locking said shaft with respect to said gear.

5. In a device of the character described, a type or die bed, suitably actuated, a sheet-carrying apron, a gear, a shaft upon which 110 gear is loosely mounted, means for directly actuating said gear, frictional means for engaging said gear with said shaft, means locked to said shaft for actuating said apron and means for locking said shaft against rotation, said locking means automatically disengaging said gear from said shaft.

6. In a device of the character described, a type or die bed suitably actuated, a sheet-carrying apron, a shaft, a gear suitably secured to said shaft for actuating said apron, a drive-gear suitably actuated and loosely mounted on said shaft, a spring bearing against said drive-gear and normally locking the same with respect to said shaft and a lock 115 for arresting the rotation of said shaft.

7. In a device of the character described, a type or die bed suitably actuated, a sheet-carrying apron, a shaft, a gear suitably secured to said shaft for actuating said apron, 120

130

4
 a drive-gear suitably actuated and loosely mounted on said shaft, a spring bearing against said drive-gear and normally locking the same with respect to said shaft, a lever 5 suitably controlled and a cam-shoulder on said shaft with which said lever contacts to lock the shaft against rotation.

8. In a device of the character described, a type or die bed suitably actuated, a feed-cylinder, a feed-table, means for reciprocating said cylinder toward and away from said table, suction devices for said cylinder, grippers for engaging the sheet, feed-tapes and means for carrying the sheet to the proper 15 position with respect to the dies from said tapes.

9. In a device of the character described, a type or die bed suitably actuated, a feed-cylinder, a feed-table, means for reciprocating 20 said cylinder toward and away from said table, a sheet-abutment and support suitably actuated, a suction means for said cylinder, feed-tapes for carrying the sheet from said cylinder, side guides for said sheets, sheet- 25 stops, and an apron for carrying said sheets, said apron being automatically controlled.

10. In a device of the character described, a type or die bed suitably actuated, a lever suitably actuated, a feed-cylinder carried by 30 said lever, grippers supported with respect to said cylinder and adapted to rotate there-

with, a cam carried by said lever, a lever or dog actuated thereby and adapted to actuate said grippers, an abutment adapted to be actuated as the cylinder is actuated and suction means for said cylinder. 35

11. In a device of the character described, a type or die bed suitably actuated, a stationary platen, side guides for the sheet, mounted on said platen, rock-shafts mounted in journals on said platen and extending along the side guides and parallel therewith, sheet-stops carried by said shafts, means suitably actuated for partly rotating said shafts to raise said stops and automatic 45 means for returning the stops to their operative position. 40

12. In a device of the character described, a type or die bed suitably actuated, a stationary platen, side guides for the sheet 50 mounted on said platen, rock-shafts mounted in journals on said platen and extending along the side guides and parallel therewith, sheet-stops carried by said shafts, means suitably actuated for partly rotating said shafts to raise said stops and springs for returning the stops to their operative position. 55
